UNITED STATES PATENT OFFICE.

ARTHUR ANSELL DIX, OF ORANGEBURG, SOUTH CAROLINA.
LUBRICATING-OIL DISPENSER AND DISPLAY DEVICE.

1,412,780.

Specification of Letters Patent. Patented Apr. 11, 1922.

Application filed August 2, 1921. Serial No. 489,272.

To all whom it may concern:

Be it known that I, ARTHUR A. DIX, a citizen of the United States, residing at Orangeburg, in the county of Orangeburg and State of South Carolina, have invented 5 certain new and useful Improvements in Lubricating-Oil Dispensers and Display Devices, of which the following is a specification, reference being had therein to the accompanying drawing.

This invention relates to lubricating oil dispensers, and more particularly to a lubricating oil dispenser and display device, having for its principal object the provision of 15 a simple and effective means for dispensing oil under pressure and for utilizing the source of pressure as a means for producing a pleasing display of the oils for sale.

Another object of the invention is the provision of a dispensing stand, having means 20 for dispensing the oil and embodying visible oil containers showing the character and quality of the oil to be dispensed, and utilizing lights for illuminating such oils so that 25 they may be displayed at night.

Another and essential object of the invention is the provision of a dispensing device for lubricating oils, which utilizes a source 30 of pressure for dispensing the oils, such pressure also being employed to assist in displaying, by bubbling up through oil held in 35 visible containers.

A still further object of the invention is the provision of a combined dispensing and 40 display device, embodying visible oil containers with means for causing a source of air pressure to bubble through the oil, and utilizing electric lights in such manner that various colors and remarkable color reflections are produced.

Further objects of the invention will appear as the full and specific description is read in connection with the accompanying drawings, which form a part of this application, and in which—

Figure 1 is an elevation of the combined dispensing and display device, with mechanism for feeding oils thereto illustrated diagrammatically.

Figure 2 is a vertical sectional view taken through the dispensing stand.

Figure 3 is a detailed horizontal section, said section taken on the line 3—3 of Figure 2.

Figure 4 is a horizontal sectional view taken on the lines 4—4 of Figure 2, and

showing the relative position of the dispensing faucets to the oil pans.

Figure 5 is an elevation of the lower part of the dispensing stand, and showing the opening in said stand through which access might be had to the couplings of the oil and air supply pipes.

Referring more particularly to the drawings, S generally represents the stand, which consists of a cylindrical body 1, mounted upon a base 2, suitably flared to provide the proper footing, and which, as usual in dispensing devices of this type, is bolted to a concrete or other similar foundation. The body 1 is preferably cylindrical in outline and is provided, adjacent to the base, with a hand-hold opening, closed by plate 4, so that access may be readily had to the couplings of the oil supply pipes to be herein- 75 after described.

Adjacent to the upper portion of the base, I provide an opening elongated longitudinally of the casing and provided on opposite sides thereof with outstanding and laterally turned ribs 6, upon which slides the closing door 7. This door is preferably limited in its closing movement by stops 8 and may be locked in such position by putting a pad lock through the corresponding ears 9, formed on the door and the body as shown.

At or adjacent the bottom of the opening and preferably dividing the body into upper and lower compartments, is a diaphragm 10, upon which the oil-drip pans may be supported. The upper portion of the casing has secured thereon an angular casting 11, with a plurality of vertical circular flanges 12, in which are received suitable packing gaskets 13, adapted to receive the lower ends of the glass oil containing tubes 14. Mounted upon the top of the tubes 14 is a plate 15, having depending vertical circular flanges 16, with packing gaskets 17 therein to rest upon the top of the tubes. The plate 15, and the casting 11, are held together with gaskets 13 and 17, compressed upon the ends of the tubes by means of a plurality of bolts 18, passing through the lateral flanges 19, of the casting 11 and the plate 15, as shown.

The center portion of the plate 15, has projecting therefrom an annular collar 20, in which is seated a transparent or semi-transparent globe 21, for a purpose to be hereinafter described.

Having now described generally the structure of the stand proper, I shall proceed to

describe the method of dispensing oils therefrom, and then describe the method of displaying the oils.

22 represents a suitable supply tank, connected to a compressor or other suitable source of pressure, through a pipe 23. This tank, as shown, is provided with a pressure gauge 24 and with an outlet pipe 25, in which is located a controlling needle valve 10 26, a pressure regulator 27, a safety or pop valve 28, and a second or low pressure gauge 29. The gauge 24 is adapted for high pressure indication and the regulator 27 is adapted to reduce the pressure from approximately 300 pounds to 20 pounds, or some fraction thereof, which will be indicated upon the gauge 29. The pressure tank can be located at any suitable point, and the outlet pipe 25, may be laid under the ground, as 15 shown, to a point where the supply tanks 29' and 30 are located.

I then conduct suitable branch pipes 31 and 32, from the pipe 25 to the tops of these tanks with suitable valve 33, therein, where- 25 by the pressure may be cut off of any tank, as will be readily understood. The tanks are supplied with suitable filler pipes 34, having air tight caps 35 secured thereto. They are also supplied with outlet pipes 36 and 37 lead- 30 ing to the bottom of the tanks as shown. These outlet or feed pipes are conducted up to the base and through the body where they are connected by unions 38, to the dispensing pipes 39 and 40, which lead up through the 35 body and the diaphragm, and are threaded into the casting 11, at the point where they communicate with the interior of the tubes 14. Each pipe is provided with a faucet 41, preferably of the thumb-clip type, and also 40 with needle valves 42, which are supplied to control the flow of oil to the display tubes 14.

As shown, the air supply pipe 25 is also passed up through the base and connected by union 43, to a pipe 44, which is joined by a 45 T-coupling and suitable unions with the pipes 39, above the needle valves 42. The pipe 44 is also supplied with a needle valve 45, and each of the branch pipes leading to the pipes 39 and 40 are provided with needle 50 valves 45' and 46, by which air may be cut off from either or both of the display tubes 14.

As shown in Figure 2, the diaphragm is provided with suitable apertures, and ex- 55 tending below the diaphragm are webs which project diagonally in opposite directions, so as to form sumps 46' from which the oil drippings may be removed by pet-cocks 47.

In the operation of the device, it will be 60 readily seen that twenty pounds pressure is maintained on the tanks 29 and 30 so long as the valves 33 remain open. The pressure on top of the oil in the tanks 29' and 30 forces the same up through the pipes 36 and 65 37 and 39 and 40, to the faucets 41, where it

may be readily dispensed in the usual manner. By opening the valve 42, oil will flow through the extensions of the pipes 39 and 40, into the transparent display tubes 14, where it may be readily inspected. By open- 70 ing the valves 45' and 46, and properly ad- justing the same, a uniform bubble may be caused to pass through the oil and out through a suitable vent in the plate 15, the valves 42 being, of course, closed at this time. 75

In order that the oils may be displayed at night, and various color reflections shown which are caused by the bubbles, there is passed up through the casing a pair of conductors 49, leading to electric lamps 50, 80 mounted upon a tubular standard 51, ar- ranged between the plates 11 and 15. This tubular standard carries the containers and lamps, and extends up into the frosted globes 21, where an additional light 52 is placed. 85 Any suitable indicia may be printed upon the globe, as for instance that shown in Figure 1. The reflection of the electric lights shin- 90 ing through the oil, and bubbles constantly passing through, provide a unique form of display and many remarkable color reflec- 95 tions are produced, which are not only at- tractive to the eye of the observer, but which serve to further display the character and quality of the oils to the customer and in- 95 crease sales.

While I have shown two dispensing pipes and two display containers, so as to show that the device is adaptable for dispensing more than one grade of oil, I wish it to be under- 100 stood that the same schematic arrangement may be carried out for a great number of grades of oil, such as for instance, very light, light, medium, medium heavy, heavy and extra heavy. In such case, of course, the dis- 105 play containers can be arranged in a circle around the electric lights, which would be located centrally so as to throw their rays through all the containers.

What I claim is:—

1. In a liquid dispensing device, a source 110 of liquid supply, means for feeding the liquid to the point of dispensing, visible display containers holding a maintained quantity of liquid therein, and means for utilizing the feeding means for producing constant agitation in the liquid contained in the visible containers.

2. In a dispensing and display device for liquids, a source of liquid supply, means for feeding liquid from the source to the point of dispensing, transparent liquid containers, means for filling said containers from the source of supply and maintaining a quantity of liquid therein, including in part the 120 feeding means and means for utilizing feed- 125 ing means for producing constant agitation in the liquid held in the containers.

3. In a combined dispensing and display device for liquids, a source of liquid supply, 130

- means for feeding the supply to the point of dispensing, transparent liquid containers, means for controlling the flow of liquid to said containers and maintaining a quantity of liquid therein, means for utilizing the feeding means to maintain constant agitation of the liquid in the containers, and means for producing color reflections from the liquid in the containers.
- 10 4. In a combined dispensing and display device for liquids, liquid containers, a source of pressure for feeding the liquid in the containers to the point of dispensing, transparent display containers, means permitting the feeding of a pre-determined quantity of the liquid to the display containers, and maintaining a quantity therein, and means for connecting the source of pressure to the visible containers for producing a uniform bubble therethrough.
- 15 5. In a combined dispensing and display device, a source of liquid supply, a source of fluid pressure supply connected thereto, display containers, means for conducting the liquid from the source of liquid supply to the point of dispensing and to the display containers, means for controlling the supply to the display containers and maintaining a quantity of liquid therein, and means for connecting the pressure supply to the display containers and for regulating the entrance of the pressure to the containers for producing a uniform bubble circulation through the containers.
- 30 6. In a combined dispensing and display device, a source of liquid supply, a source of fluid pressure supply connected thereto, display containers, means for conducting the liquid from the source of liquid supply to the point of dispensing and to the display containers, means for controlling the supply to the display containers and maintaining a quantity of liquid therein, and means for connecting the pressure supply to the display containers and for regulating the entrance of the pressure to the containers for producing uniform bubble circulation through the containers, together with means for illuminating the containers.
- 45 7. In a combined dispensing and display device for liquids, liquid supply tanks, a source of fluid pressure supply connected to said tanks, transparent display containers, means for conducting the liquid from the tanks under pressure to the point of dispensing, and to said containers, means for controlling the flow to the containers and maintaining a quantity of liquid therein, means for connecting the fluid pressure supply to the containers, and valves for controlling the fluid pressure supply to the containers, said containers being vented.
8. In a combined dispensing and display device for liquids, liquid supply tanks, a source of fluid pressure supply connected to said tanks, transparent display containers having a maintained quantity of liquid therein, means for connecting the source of fluid pressure supply and the containers, means for regulating the amount of fluid pressure supply to the containers for producing a uniform bubble circulation through the liquid therein, and means associated with the display containers and coacting with the bubbles to produce multi-colored reflections from the liquid.
- 15 9. In a combined dispensing and display device for liquids, liquid supply tanks, a source of fluid pressure supply connected to said tanks, transparent display containers having a maintained quantity of liquid therein, means for connecting the source of fluid pressure supply and the containers, means for regulating the amount of fluid pressure supply to the containers for producing a uniform bubble circulation through the liquid therein, and electric lights associated with the containers and arranged to co-act with the bubbles to produce multi-colored reflections from the liquid.
- 30 10. In a liquid dispensing and display device, a source of liquid supply, means for feeding the liquid from the supply to the point of dispensing, a visible display containing means for maintaining a constant quantity of liquid therein, and means for utilizing the feeding means for producing a uniform bubble circulation through the liquid in the container.
- 45 In testimony whereof I affix my signature in the presence of two witnesses.
